UNITED STATES PATENT OFFICE.

JOHN P. HICKEY, OF NEW YORK, N. Y., ASSIGNOR, BY MESNE ASSIGNMENTS, TO
JAMES M. CRANK, OF NEW YORK, N. Y.

BUILDING STRUCTURE.

Application filed September 4, 1924. Serial No. 735,856.

This invention relates to buildings, and more particularly to structural elements constituting movable closures forming part of exterior or interior walls, partitions, doors, 5 windows and skylights, although the improvements may be utilized in any field for which they are adapted by their nature.

An important object of this invention is to provide such a movable closure of flexible material with means to clamp it firmly 10 along one or more of its margins in position to occupy that portion of the wall or other structure where it is to serve as a closure, the term "closure" not being employed in a restricted technical sense to indicate a weather-excluding structural element, as the novel closure structure may be either completely or partially weather-excluding, and opaque or light-transmitting, as 15 occasion may require.

Another important object of this invention is to provide a series of such movable closures, combined in extended relation with each other in such a manner as to constitute 20 the wall of a building, or a substantial portion thereof, with clamping means provided to hold the respective sections in place by engagement therewith around their margins.

Still another object of the invention is to 25 provide a frame work of telescopic structure with marginal means to hold said movable closures, so that the manufacturer thereof may stock a series of sizes of standard lengths or widths, each of the series being 30 capable of sufficient telescopic adjustment to permit their application for closure of spaces varying somewhat from the nearest standard dimension, thus making it possible to fit readily such wall apertures as windows 35 or doorways without the necessity for cutting or making other mechanical alterations in the framework or clamping members, and also permitting the installation of the appliance as a unitary structure by the use of 40 only ordinary tools, such as a screw-driver.

Referring to the drawings:—

Figure 1 is a vertical section of a structure embodying this invention.

Figure 2 is a fragmentary horizontal section 50 on the line 2—2 of Figure 1.

Figure 3 is a front elevation of a modified structure.

Figure 4 is a vertical section on the line 4—4 of Figure 3.

Figure 5 is a detail view in side elevation

on an enlarged scale, looking in the direction of the arrow 5 in Figure 3.

Figure 6 is a horizontal section on the line 6—6 of Figure 5.

Figure 7 is a detail view on a larger scale 60 in vertical section on the line 7—7 of Figure 3.

Figure 8 is a fragmentary, detail view 65 in side elevation, on a larger scale, taken in the direction of the arrow 8, Figure 3.

Figure 9 is a view in front elevation of a modification.

Figure 10 is a vertical section of the appliance shown in Figure 9, isolated.

Figure 11 is a fragmentary detail view 70 of the lower left-hand corner thereof.

Figure 12 is a fragmentary detail view 75 in horizontal section on the line 12—12 of Figure 10.

Figure 13 is a fragmentary view in vertical section, similar to the lower portion of Figure 10, but looking in the opposite direction.

In the embodiment of this invention selected for illustration and description in 80 Figure 1, the parts designated by the reference characters 11 and 12 are upright metal structural members, respectively of T section and L section, joined by horizontal metal members 13 and 14 of L section, to 85 form a framework which may be considered as part of the side-walls of a bungalow, which may be entirely constructed in like fashion to the portion illustrated, which comprises a complete side panel 15 adjacent 90 to the corner; also a fragment of an adjoining side panel 16, in elevation; and shows in section the adjoining end panel 17.

In each panel is shown a flexible closure member 18, preferably of waterproof textile fabric, either metal or cloth, carried by conventional rollers 19 journaled at 20 in fixtures mounted on the webs 21 of the vertical members 11, and at 22 in fixtures on webs 23 forming part of the corner structure 100 formed by the vertical members 12.

In accordance with this invention, I provide elongated, L-shaped clamping members 24 and 25 overlapping the lateral margins of the flexible closure members 18, to hold 105 the latter against displacement, these clamping members being supported on the webs 21, 23 and 17 respectively and actuated by levers 26 which are mounted on bolts or screws 27 secured to the webs, the levers 110

having cam-portions 28 which engage the clamping members 24 and 25 and force the same toward the vertical flanges of the members 11, 23 and 17 when the levers 26 are turned into the position illustrated, whereby the clamping members are caused to grip the lateral margins of the closure members 18. 5

Where desirable, separately formed fixtures 29 may be secured to the framework to support the cam-levers, and in general their structure may be modified to meet conditions found in use. They are preferably slotted, as shown at 30 in Figure 5, to permit a slight play on the posts 27. 10

It will be understood that this invention is not limited to use in connection with closure members of open mesh fabric or other 15 ventilating construction, and I have shown in Figure 1 closure portions 18^a which may be considered to be formed of flexible, closely woven material, such as canvas, so as to be weather-proof, the same being wound upon rollers 19 at the bottom of the framework. These rollers may be carried by fixtures 22 20 similar in every respect to those already described, and bearing the same reference characters so that special description thereof is not necessary, and clamping members are shown also bearing reference characters 25 like those already described. 30

As a matter of convenience, where it is desired to use both forms of closure in the same panel, they may be joined as indicated at 31 and provided with an operating handle 31^a, so that half the window can be ventilating and the other half of weather-proof material or, if desired, the closure may be so operated as to utilize the ventilating material for the entire panel, or weather-proof material for the entire panel, as indicated at 40 the right-hand side of Figure 1. When rollers are thus provided at the top and bottom, they are preferably made of the well-known spring type, in order to keep the closure under tension. An example of such 45 spring roller construction is shown in greater detail in the larger scale figure Fig. 10, it being understood that the section of this figure so far as it applies to the roller may be considered as a section at an appropriate portion of one of the rollers 19 in Fig. 1. 50

I prefer to provide casings 32 for each of the rollers, these casings being preferably of metal and fitted to constitute dust-proof and insect-proof inclosures for their respective regions, completing the insect-excluding function of the clamping members so that the entire panel will be insect-proof, this being an important and novel feature of this 55 invention. 60

Referring to the modification illustrated in Figure 3, a single closure member 38 of flexible textile fabric is shown wound upon a roller 40 at the top of a wooden window frame 41 within which are arranged clamp- 65

ing members 25 for engagement with the lateral margins of the closure member 38, these clamping members being similar in general arrangement and function to those already described, being actuated by cam-levers 26 identical in structure with those described, but mounted on screws 27 entering the woodwork of the window frame. 70

The clamping members 25 are shown as extending the entire length of the window 75 frame, in the instance illustrated and two sets of the cam-levers 26 are shown on each side of the frame, it being understood that there may be any desired number and that the length of the clamping members may 80 be determined by the requirements of any given installation.

As shown in the illustration, I prefer to provide this type of window with metal strips 35 between the clamping members 25 and the wooden strips 34 so as to afford a metallic base for the clamping action, and these base strips may be conveniently formed as shown in Figures 5, 6, and 8 where they are illustrated as L-shaped in 90 cross section, and transfixed by the screws 27, or other independent screws may be provided to hold these base strips in place. 95

Figure 6 illustrates the clamping member 25 as having a suitable friction-strip at 45 and the base member 35 is provided with a similar friction-strip 46, and on account of the separation between the base member 35 and the clamping member 25, I prefer to form the clamping member with an offset 100 portion 48, which serves to counter-balance the aforesaid separation, and if there are no friction-strips, the offset portion 48 serves as a fulcrum about which the member 25 may have a slight resilient play under the 105 action of the cam-lever 26, and will spring back when released. 110

If desired leaf-springs 49 may be interposed between the members 35 and 25, tending normally to separate these members 115 when not constrained by the cam-levers.

In Figures 3, 4, and 7 I have shown this window appliance as having its roller 40 inclosed by a casing comprising telescopic members 50 and 51, so that the dust-proof and insect-proof character of the casing can be maintained even where the casing is not cut to fit the exact width of the window frame, and furthermore by keeping in stock telescoping casings of this character which correspond within an inch or so to the standard size of windows, it is possible to furnish a casing which can be fitted to any size of window without the necessity for any alteration of the casing in field work. 120 125

In the installation illustrated, the fixtures 52 are shown as inclosed by the casing members, being secured against the base members 35, which are extended to the top of the window frame, having each a flange 53 to 130

which the casing 51 is fitted. The clamping members 25 may have similar insect-proof flanges 53.

The window illustrated in this connection 5 is a casement window, the sash 54 swinging away from the closure, as illustrated, and the closure is provided with a cross bar 55 by which it may be readily drawn down against the sill.

10 In Figures 9-13, inclusive, I have illustrated an installation in connection with a sliding sash window of conventional construction, and in this installation the flexible closure 60 is wound upon a spring roller 61 near the sill 62, and between the uprights 63 of the window frame. The spring of said roller is shown at 61'. The roller spindles 64 and 65 are set in roller brackets 66 and 67 carried by bracket cases 68 and 69 which 15 are mounted, as by rivets 70, (see Figure 13) upon vertical metal members 71 and 72, L-shaped in cross section, and which serve respectively as the base for the clamping members 73 and 74, the latter being also 20 25 L-shaped in cross section, the lateral margins of the flexible closure 60 being clamped between the neighboring portions of the members 71 and 73 and the members 72 and 74. The members 71 and 72 are secured to the window frame by screws 75, and the clamping members 73 and 74 are actuated by levers 76 having cam portions 77 similar to those already described, each of these levers deriving its fulcrum from a post 78 which 30 35 transfixes the cam lever 76 as indicated in Figure 12, which shows the post 78 as passing through the clamping members 73 and 71, being riveted into the latter at 79.

40 Cotter pins 80 are provided, as shown in Figure 10, to secure the cam levers removably upon the posts 78, and these serve also to hold the flanges 81 of the clamping members 73 and 74 firmly in position. I prefer to form the offset bend 82 between the flanges 45 50 55 60 65 70 75 80 85 90 95 100 105 110 115 120 125 130 135 140 145 150 155 160 165 170 175 180 185 190 195 200 205 210 215 220 225 230 235 9990 9995 9999

by set-screws 88 working in slots 89, and which can be adjusted to fit windows differing somewhat in width, the flanges 85 having lips 90 to co-operate with the slides 87. This carries out an important feature of my invention, which is to enable a series of sizes of the appliance to be carried in stock and adjusted to standard sizes of windows without the necessity for altering the appliance on the job, or using tools other than those readily found in any household, and the insect-proof character of the closure is also served by the provision of these telescopic slides.

I prefer to form the roller sockets 66 and 67 integrally with the bracket parts 68 and 69 respectively, the socket 66 being formed with a round hole 91, to receive the round roller spindle 64, and the socket 67 being formed with a slot 92 to receive the flat spindle 65 of the roller. Such spindles characterize conventional rollers of the spring actuated type shown in Figs. 10, 11, and 13 in detail, and which I prefer to utilize throughout the different embodiments of my invention selected for illustration, their operation and installation being well understood in the art, and not requiring special description. Ordinarily they may be used to advantage without the catch usually provided on shade rollers, inasmuch as the marginal clamps hold the flexible closure in any desired position, making possible a more exact adjustment than can be secured by roller catches, and avoiding the "hitching" movements which are characteristic of catch-operated shade rollers.

To facilitate the easy and steady operation of a rolling screen having only a spring roller at the bottom, as shown in Figs. 9 and 10, I prefer also to provide the flexible closure 60 with a binding of suitable material, such as the metallic strip shown at 93, which has slots 94 that may be engaged with projections 95 upon sash hooks or finger holds 96 of special shape secured in place on the sash 97 by screws 98. When thus equipped, the act of raising the sash serves to draw the closure 60 upward with it automatically so that the insect-proof character of the closure is maintained at all times, regardless of the extent to which the sash is raised. The spring roller maintains the closure under tension, keeping it flat and smooth, and winds it up automatically when the sash is lowered.

Where two such rollers are provided, as at 19 in Fig. 1, they operate in balanced relation to keep the closure under tension, and render its movements easy. Having illustrated and described my invention thus fully, and suitable means by which the same may be carried into effect, I wish it to be understood that I do not

limit myself to the materials or details of structure selected for illustration and description, nor in general do I limit myself otherwise than as set forth in the claims read 5 in connection with this specification.

What I claim as new and desire to secure by Letters Patent, is:—

1. A structure of the class described comprising a plurality of extended frame members adapted to be mounted in spaced relation, and having means to support rotatably therebetween a roller provided with a flexible closure for the framed space, separately formed, removable marginal clamping means 10 comprising members mounted tiltably in parallelism with said frame members, and adapted to secure said closure to said frame members, means to tilt said clamping members operatively, a cover member to enclose said roller, and means to support said cover member upon said frame members.

2. A structure of the class described comprising a plurality of frame members adapted to be mounted in spaced relation, and having means to support a roller journalled therebetween and provided with a flexible closure for the framed space, marginal clamping means to secure said closure to said frame members, a cover member to enclose 25 said roller, means to support said cover member upon said frame members, and means to conform said cover member interchangeably to different spacings of said frame members, said means including a slide movable lengthwise upon said cover member.

3. A structure of the class described comprising a plurality of frame members adapted to be mounted in spaced relation, and having means to support a roller journalled 40 therebetween and provided with a flexible closure for the framed space, marginal clamping means to secure said closure to said frame members, a cover member to enclose said roller, means to support said cover member upon said frame members, and means to conform said cover member interchangeably to different spacings of said frame members, said means including a slide movable lengthwise upon said cover member, said slides 45 interlocking respectively with said frame members to hold said cover in place.

4. A clamping device for structural elements of the class described, comprising a frame strip provided with a post, a clamping 55 strip apertured to fit upon said post in position to embrace and clamp a flexible closure member in co-operation with said frame strip, and an operating lever secured remov-

ably upon said post, and operable to cause said clamping action, said clamping strip 60 being removable freely from said frame strip upon removal of said lever from said post.

5. A clamping device for structural elements of the class described, comprising a metal frame strip, a separately formed tilt- 65 able metal clamping strip, means to secure said strips in assembled relation to embrace and clamp a flexible closure member, an operating device to cause said clamping action, and means to cause separation of said clamp- 70 ing strip and frame strip when released by said operating device.

6. A structure of the class described comprising a plurality of L-shaped metal frame members adapted to be mounted in spaced 75 relation at each side of a roller journalled therebetween and provided with a flexible closure for the framed space, and separately formed L-shaped metal strips adapted to clamp the margins of said closure to said frame members, and an operating device for each of said clamping members, said clamping members being of resilient construction to cause clearance thereof from said closure when said operating devices are released. 80

7. A structural element comprising an apertured framework, a flexible closure for the apertured portion of said framework, and a plurality of spring rollers upon which said closure may be wound, alternately, said 85 rollers being mounted in fixed position respectively upon said framework in balanced relation, with said closure maintained under tension therebetween.

8. A structure comprising a framework, 90 and a plurality of flexible closures constituting the wall of said structure, said closures being each formed partly of ventilating and partly of weather-excluding material and spring rollers in balanced relation upon 95 which said closures are wound under tension therebetween.

9. A structure comprising a framework, and a plurality of flexible closures constituting the wall of said structure, said closures 100 being each formed partly of ventilating and partly of weather-excluding material and spring rollers in balanced relation upon which said closures are wound, under tension 105 therebetween, and means to clamp said closures to said framework along their lateral margins.

Signed at New York, in the county of New York and State of New York this 25th day of April, 1924.

JOHN P. HICKEY.
